ABSTRACT

A scaffold board construction including pads for attachment to the underside of a scaffold plank to restrain the plank from slipping longitudinally or transversely on the plank-supporting bars of the scaffold, which bars are ordinarily tubular metal, and the pads are constructed of rubbery, non-skid material the pads being of two configurations, one thicker and channelled and the other thin and planar, the thicker pads having channels to accept and grip the bars, and the thin pads engaging other planks. For convenience in attaching the thicker pads they are formed with integral nailing strips permitting the pads to be quickly and semi-permanently secured to the planks, but both pads may be secured adhesively if desired. The preferred form of plank has the thicker channelled pad at one end and the planar pad at the other end for use in overlapping series.

NON-SKID SCAFFOLD BOARD PAD

BACKGROUND OF THE INVENTION

Scaffold planks usually have flat or gently tapered undersurfaces and are often either laid loosely on the scaffold bars or ties in place with rope. One or more planks laid side by side comprise a working platform for workmen and material and the platform often has a transverse horizontal width less than the length of the corresponding scaffold bars so that the planks sometimes slip sidewise as well as encountering the more obvious hazard of longitudinal slippage. Metal cleats do not prevent sidewise slippage and require rather exact placement of the scaffold bars to prevent rocking of the planks with the result that such cleats are simply not used regularly. There exists a need, therefore, for a non-slip plank or plank pad construction which is very safe to use, convenient to adapt to existent equipment as well as economical to manufacture.

SUMMARY OF THE INVENTION

As claimed, the herein disclosed item satisfies the abovementioned need inasmuch as scaffold planks are provided with pads on the underside surface, these pads being of resilient and non-skid material with some of the pads having open channel portions at the end of each plank to accept the scaffold plank-supporting bars and planar pads at the other end of each plank. The pads have lateral nailing strips which are nailed onto the planks for substantially permanent securement of the pads or the pads may be adhesively secured.

BRIEF DESCRIPTION OF THE DRAWING

FIG. 1 is a perspective view, from the underside, of one of the thicker, channelled non-skid pad:

FIG. 2 is a side elevation view of a section of scaffolding with scaffold planks supported in series thereon with the thicker pads engaging scaffold plank-supporting bars of the scaffolding and the planar pads each engaging the next succeeding plank in a series;

FIG. 3 is an end elevation view of the structure of an end portion of the scaffolding with three planks thereon; and

FIG. 4 is an enlarged sectional view taken on line 4-4 of FIG. 3.

DETAILED DESCRIPTION OF A PREFERRED EMBODIMENT

Referring now to the drawing and particularly to FIG. 2 and 3, the scaffolding is fragmentarily illustrated as comprising upright 10 and scaffold plank-supporting horizontal bars 12 secured to the uprights as indicated at 14, the particular mode of securement of the bars 12 being somewhat immaterial to the structure and functioning of the invention claimed herein.

The planks 16 are of a length to span the space between pairs of bars 12 and of course these planks may be of constant cross-section or tapered toward the ends. As illustrated in FIG. 3 these planks will frequently not occupy the full inter-upright space on the bars 12 so that one or more spaces 18 between the planks 16 or between the planks and the uprights will occur, this introducing the hazard of sidewise slippage in addition to the hazard of endwise slippage of the planks 16.

According to my invention each plank will have secured to one side, the underside in use, at least one pad

generally indicated by the numeral 20, these pads being of a length corresponding substantially to the width of the planks 16. The pads 20 are secured near the ends of the planks and are constructed of slightly resilient, non-slip material such as synthetic rubber. Each pad 20 has two lateral nailing strips 22 and a thickened central portion 24 with an open channel 26 running the entire length of the pad centrally of the thickened portion 24, and said nailing strips 22 are similarly elongated in the same direction as said channel. The channels 26 are substantially semi-cylindrical to accept and grip the bars 12, thus preventing the plank 16 from slipping either longitudinally or transversely.

The nailing strips have spaced apertures 28 for nails or screws indicated at 30 and the nailing strips are fared or radiused into the thickened portions as indicated at 32 to assure against rupture in use. The portions of the pads at the sides of the channel 26 have a very considerable thickness for strength and durability and these portions at the sides of the channel terminate in flat faces 34 of considerable area to withstand abrasion such as that encountered when the planks are stacked one on top of the other for storage and transportation.

The pads 20 are preferably secured to one end only of each plank and since the planks will ordinarily be assembled in overlapping series, such as indicated in FIG. 2, each plank has secured thereto, on the same side as the pad 20 but near the opposite end of the plank, a thin planar sheet or pad 36 which will ordinarily be adhered in place, extending across the plank, and of rubber non-slip material to engage the next succeeding plank and prevent sidewise slippage of the uppermost plank.

It is noteworthy that since lengthwise slippage of the planks is presented the length of the planks may be shorter than ordinary plain planks and the saving in plank material offsets the cost of the pads 20 and 36.

Obviously the proportions of the pads may be varied and the positioning thereof on the planks and even their number on each plank may be resorted to without departure from the spirit and scope of this invention, but what I claim as new and wish to secured by Letters Patent is:

1. Scaffold equipment particularly for use with scaffolding framework having horizontal cylindrical plank-supporting bars, said equipment comprising:
a scaffold plank dimensioned to extend across and span the space between a pair of said bars at substantially the same level;
one pad on the underside of said plank, extending transversely thereof and positioned adjacent to one end of the plank;
attachment means to secure said one pad on said plank;
said one pad being resilient material for non-slip engagement on said bars and having an open channel portion extending longitudinally thereof and dimensioned to fit snugly upon one of said bars and thus in use capable of preventing slippage of the plank both longitudinally and transversely of said bars; a second pad on each plank on the same side thereof as the first mentioned pad and near the opposite end of the plank, said second pad being sheet-like and of rubbery non-slip material to engage the upper surface near the end of the next suc-

ceeding plank wherein planks are laid in end-overlapping relationship as in a scaffold.

2. Scaffold equipment according to claim 1 wherein said one pad has thickened portions between said nail-ing strips and said channel portion, said thickened por-

4
tions terminating in flat faces of considerable area to withstand abrasion encountered when the planks are stacked or overlapped one on top of the other.
